Thomas P. Edman

Letters Patent

The Schedule referred to in these Letters Patent and making part of the same containing a description of the device of the said Thomas P. Edman himself of his Improvement being a mode of Conveying Oil, & Water & Mineral water, and applying them in such a manner as to prevent damage to the said machinery.

As many hours as other suitable animals as are necessary are placed in a receding platform constructed in the following manner. Several cylindrical pieces of wood are being together and fastened round two large stones or cylinders which form a receding, platform. They are made to form a horizontal flap to which is attached a number of forcing pumps by iron rods. These they raise Water from a certain and pour it into a cylinder in which they stand. The air within this cylinder is not suffered to escape consequently the pressure of water from the pumps impinges the air on the surface the elastic force of the compressed air forces the water from the cylinder. Also a tube leading from the bottom of the cylinder into the cylinder the water goes the top bottom & occupies a piston or diaphragm within this cylinder and escapes this by pipes one leading from below the other leading from the bottom of this cylinder into the bottom from whence it is taken up where it is again taken up and goes to the place where it is to be applied.

Conveying a pump is attached to the said platform cylinder in which there is used to give the air to the purpose of several descriptions. There is likewise on the same cylinder a pipe or tube to allow the purpose to these, on the staff that the pump are attached to the eccentric are placed at different angles so that the water may be forced in repeatedly which keeps up the pressure of the air within.

There is also in each of the shafts a valve or valve for regulating the motion of the water in the said cylinder. Also a pump above the pump above the pump and

75484

intended in a suspension with the Water Pump & Water the other working in
the cylinder the same as the Water Pump Machine the propeller may be
attached either by Cranks or Bevels to the piston rod or shaft of the pump
or said Cylinder & the Velocity may be increased or decreased by increasing
or decreasing the size of the Domes that the pump runs on.

That claim is my in-

vention & necessary as the vacuum horse mounted of Cylinder & Pump &
spying the horse specific power to a propell various kinds of machinery

and. witness
